UNITED STATES PATENT OFFICE

2,498,190

MIXING DEVICE

Leonard M. Weeks, Milwaukee, Wis.

Application April 30, 1948, Serial No. 24,361

4 Claims. (Cl. 48—180)

1

The present invention relates to mixing devices and it consists in the combinations, constructions and arrangements of parts herein described and claimed.

It is an object of the present invention to provide a mixing device which may be incorporated in an internal combustion engine to ensure more nearly perfect carburation.

Another object of the invention is the provision of a mixing device having no moving parts and which will cause a whirling of the gas and air mixture passing therethrough in a novel and efficient manner.

Another object of the invention is the provision of a mixing device having automatic means for whirling a gaseous mixture in one direction and means for reversing such whirling motion with a correspondingly greater admixture of the contents of the matter passing through the device.

Another object of the invention is the provision of a device of the character set forth which is simple and inexpensive in its construction and economical and efficient in use.

Other and further objects of the invention will become apparent from a reading of the following specification taken in conjunction with the drawing, in which:

Figure 1 is an elevational view, partly in section, of an embodiment of the invention in use with an internal combustion engine,

Figure 2 is a vertical sectional view taken along line 2—2 of Figure 4,

Figure 3 is a sectional view taken along line 3—3 of Figure 2,

Figure 4 is a perspective view of the device forming the invention, and

Figure 5 is a top plan view of the device.

Generally there is provided a mixer for internal combustion engines comprising a substantially cylindrical perforated insert having a flange 40 at one end for fastening the same in position in an intake pipe. The body is cut away upon one side and a series of spiralled fins provided along the bottom and a further series of oppositely spiralled fins provided along the bottom edge of 45 the cut away portion of the device. The fins extend only part way toward the center of the device thereby leaving an uninterrupted passage through the center thereof.

Referring more particularly to the drawing, there is shown therein a mixing device for internal combustion engines comprising a single piece of perforated material, preferably brass or the like and formed into a substantially open ended cylinder 10 having an annular flange 11.

2

One half of the lower part of the cylinder 10 is cut away and a series of inwardly extending spiral fins 12 formed on the resulting lower edge thereof. The lower end of the remaining one half is formed with a series of inwardly extending spiralled fins 13 which are oppositely spiralled to the fins 12. A central passage 14 is left unimpeded.

The mixer is snugly mounted in an intake pipe 15 leading to an intake manifold 16. The pipe 15 is provided with a flange 17 which is joined with a flange 18 of a pipe 19 by means of bolts 20. The flange 11 of the mixer device is held between the flanges 17 and 18.

In operation, it will be apparent that a mixture of gas and liquid fuel is fed from a carburetor (not shown) through a jet 21 which directs its force against a butterfly valve 22 which, in turn, will cause the flow of mixture to be first directed 20 against the fins 12. The fins 12 will cause the mixture to assume a whirling motion and at the same time direct a goodly portion of the mixture to the fins 13 which, being oppositely spiralled, will further admix the gasoline particles with the air in the mixture coming from the carburetor. The now fully carburated mixture will pass into the intake manifold 16 and be fed to the various cylinders of the engine in conventional manner. The central passage 14 is provided so as not to impede the flow of mixture from the carburetor to the intake manifold. It will be understood that by providing a more nearly complete mixture of gas and air to the cylinder that there is less possibility of liquid gasoline droplets forming upon the sides of cylinders to thereby impair the efficiency of the engine and to add carbon deposits thereon.

While but one form of the invention has been shown and described herein, it will be readily apparent to those skilled in the art that many minor modifications may be made without departing from the spirit of the invention or the scope of the appended claims.

What is claimed is:

1. A device of the character described comprising a hollow cylindrical body having one half of one end cut away and formed with a plurality of spiral fins and having the remaining lower end formed with a plurality of oppositely spiralled fins.

2. A device of the character described comprising a hollow perforated cylindrical body having one half of one end cut away and formed with a plurality of spiral fins and having the re-

maining lower end formed with a plurality of oppositely spiralled fins.

3. A device of the character described comprising a hollow cylindrical body, an outwardly extending flange at one end, a series of spiral fins extending half way around the other end, an extended portion of the body opposite said fins and a second series of oppositely spiralled fins formed in said extended portion.

4. A device of the character described comprising a hollow perforated cylindrical body, an outwardly extending flange at one end, a series of spiral fins extending half way around the other end, an extended portion of the body opposite said fins and a second series of oppo-

sitely spiralled fins formed in said extended portion.
